Inventor.

Robert Crawford Johnson
By his Atty. *Louis Present Whittaker*

UNITED STATES PATENT OFFICE.

ROBERT CRAWFORD JOHNSON, OF ROXTON, LEICESTER, ENGLAND.

CURTAIN RAIL AND SUPPORT THEREFOR.

Application filed February 26, 1926, Serial No. 90,906, and in Great Britain March 16, 1925.

This invention relates to the rails for carrying the runners for curtains and the brackets for supporting the said rails, of the kind in which the said brackets are recessed to house 5 the controlling cords.

Hitherto the said rails and recessed brackets have been secured in position on a wall or other surface by screws passed through both the rail and the brackets.

10 According to the invention I provide for fixing the rails to the recessed brackets and the latter to a wall or other surface, independently, without the aid of additional or extraneous means.

15 In a suitable arrangement for carrying out the invention each recessed bracket is formed on its rear surface with a screw integral or rigid therewith, for engagement with the wall or other surface by rotation of the

20 bracket, and the latter is also provided on its front surface with a flanged or headed stud constituting a hook also integral therewith, the rail being provided with slots to engage the studs and secure it to the brackets. The

25 flange or head of the stud passes through the slot, and the rail is then displaced to engage it behind the said flange or head.

The rail may be recessed lengthwise intermediate of its edges to receive the heads of 30 the studs.

To enable the invention to be fully understood I will describe it by reference to the accompanying drawing, in which:—

Figure 1 is a sectional elevation showing 35 a rail for curtain runners and a supporting bracket therefor constructed in accordance with the invention.

Figure 2 is an elevation at right angles to Figure 1.

40 Figures 3 and 4 are, respectively, a front view and a side view of one of the supporting brackets.

Figure 5 is a section of a modified form of rail.

45 *a* is the supporting rail for the curtain runners, one of which is indicated in section at *b*, Figure 1, and *c*, *c* are the brackets for supporting the said rail. As shown in the drawing each bracket is furnished with two recesses *c*¹, *c*¹ for the controlling cords. *d* is

50 the screw rigid with the rear part of each bracket *c* for engagement with the wall or the like *e*, as indicated in Figure 1, by rotation of the bracket, and *f* is the flanged or headed stud or hook provided on the front surface of each bracket and rigid therewith.

g, *g* are the slots in the rail to engage the studs *f*, *f* as shown in Figures 1 and 2, the flange or head *h* of each stud *f* being passed through a slot *g* and the rail displaced to fit 60 behind the said flange or head (the outer edge of each bracket is provided with vertically disposed portions, indicated at *c*² and *c*³, respectively, above and below the stud, *f*, against which the rear face of the rail, *a*, engages, and the head, *h*, of the stud, *f*, is separated from the portion, *c*², by a recess, indicated at *h*¹, of substantially the same width as the thickness of the rail at that point, the rear face, *h*², of the upwardly extending portion, or head, of the stud, engaging the front face of the rail and holding the rail in vertical position so that the runners, *b*, can move longitudinally of the rail throughout its entire length without undue friction with the 70 rail and without striking the studs, *f*). *i* is the recess formed lengthwise of the rail *a* to receive the heads of the studs *f*, so that the said heads do not project into the path of the runners *b*. In the form of rail shown in 80 Figures 1 and 2 the sides of the recess *i* are each at an angle to its base which is greater than a right-angle whereas in the form of rail illustrated in Figure 5 the sides are each at a 85 right-angle to the base.

Having now particularly described and ascertained the nature of my said invention and in what manner the same is to be performed I declare that what I claim is:—

1. In a device of the kind described, the 90 combination with a curtain rail for supporting a plurality of curtain runners, said rail being provided at separated points with slots extending through vertically disposed portions of the rail, of a plurality of brackets 95 each provided at one end with means for securing it to the wall and at the opposite end with a vertically disposed end face for engaging the rear face of the rail, and having a stud projecting therefrom and adapted to extend through one of the slots in the rail, said stud being provided with an upwardly extending head separated from the adjacent vertical end face of the bracket a distance substantially equal to the thickness of the rail 100 adjacent to the slot therein to enable the head to hold the rear face of the rail in engagement with the said vertical end face portions of the bracket and maintain the rail in vertical position to permit free movement of the runners throughout the length of the rail, said 105 slots in the rail being of sufficient size to per-

mit the passage of the studs and the heads thereof therethrough.

2. In a device of the kind described, the combination with a curtain rail for supporting a plurality of curtain runners, said rail being provided at separated points with slots extending through vertically disposed portions of the rail, of a plurality of brackets each provided at one end with means for securing it to the wall and at the opposite end with a vertically disposed end face for engaging the rear face of the rail, and having a stud projecting therefrom and adapted to extend through one of the slots in the rail, 10 said stud being provided with an upwardly extending head separated from the adjacent vertical end face of the bracket a distance substantially equal to the thickness of the rail adjacent to the slot therein to enable the head 15 to hold the rear face of the rail in engagement with the said vertical end face portions of the bracket and maintain the rail in vertical position to permit free movement of the runners throughout the length of the rail, said 20 slots in the rail being of sufficient size to permit the passage of the studs and the heads thereof therethrough, the said rail having its runner engaging portions extending laterally 25 beyond the slot thereof a distance sufficient to 30 enable depending portions of the runners to

lie closely adjacent to the rail without striking the said studs or the heads thereof.

3. A curtain runner support comprising a pair of brackets constructed to be secured to a support and project therefrom, each of said brackets having a vertically disposed front face, a hook projecting forwardly from said front face intermediate its vertical length, and a rail having spaced apertures to receive the hooks, said rail having a thickness equal 40 to the distance between the hooks and vertical face of the brackets whereby the rail is held in vertical position against the vertical faces of the brackets.

4. A curtain runner support comprising a pair of brackets constructed to be secured to a support and project therefrom, each of said brackets having a vertically disposed front face, a hook projecting forwardly from said front face intermediate its vertical length, 50 and a recessed rail having spaced apertures in the recessed portion to receive said hooks, said rail having a thickness equal to the distance between the hooks and the vertical faces of the brackets whereby the rail will be held 55 against said vertical faces, said hooks being encompassed within the recess of the rail whereby curtain runners may pass over the rail without interference by the hooks.

ROBERT CRAWFORD JOHNSON.
